UNITED STATES PATENT OFFICE

LESLIE G. WEYGANDT, OF WYNCOTE, AND PERCIVAL K. REED, OF LLANERCH, PENNSYLVANIA, ASSIGNORS TO ATLAS CONVEYOR COMPANY, OF PHILADELPHIA, PENNSYLVANIA, A CORPORATION OF PENNSYLVANIA

ASH HOPPER GATE

Application filed August 9, 1929. Serial No. 384,653.

Our invention relates to an ash hopper gate, that is to say, to a device which is adapted normally to close the bottom of an ash hopper, and which is adapted to be opened at various times to permit the discharge of the ashes from the hopper to a dump car or the like.

In modern steam engineering practice, one method of handling the ashes from under the steam boilers is to permit the same to accumulate in hoppers, from which they are subsequently discharged through a gated opening into dump cars or other means of conveyance.

In such systems of handling ashes, it has also been customary to quench the hot ashes by means of water, in which case it is necessary to use an excess quantity of water to insure the complete quenching of the ashes, and consequently provision must be made for draining this excess water from the hopper, as otherwise the same would, in some instances, soon fill the hopper; in other instances, would flood the dump cars; and in still other instances, would leak at various places into the rooms or passageways below the hopper.

The principal object of our present invention is to provide a gate for ash hoppers which is so constructed and arranged as to permit the excess quenching water to be drained from the hopper, and also to prevent the ashes from falling into and obstructing the drain structure when the gate is open.

A further object of our invention is to provide improved means for directing to the drain the water which passes down the sides of the ash gate frame.

A further object of our invention is to provide a gate for ash hoppers which is so constructed and arranged as to provide a minimum of obstruction to the passage of the ashes when the gate is open.

A further object of our invention is to provide a gate for ash hoppers which will be simple and efficient in its action, and durable in construction, whereby the same, while being relatively easy to operate, will withstand the rough usage to which devices of this character are necessarily subjected.

With the foregoing objects in view, our invention contemplates the provision, in connection with the outlet opening at the bottom

of an ash hopper, of a gate structure which is provided with a stationary drain trough adapted to receive and carry away the excess quenching water, and is also provided with means adapted to be automatically operated upon the opening of the gate to prevent the ashes from falling into the drain trough when they are being discharged from the hopper.

Our invention further contemplates means for operating the device for protecting the drain trough, whereby it will be moved to the operative position immediately after the gate begins to open, and will be retracted only just before the gate is fully closed.

The nature and characteristic features of our present invention will be more readily understood from the following description, taken in connection with the accompanying drawings forming part hereof, in which:

Fig. 1 is a vertical, central, sectional view of an ash hopper having associated therewith a gate embodying the main features of our present invention, the gate member being shown in the closed position;

Fig. 2 is a side elevation of the gate structure, the gate being shown in the closed position;

Fig. 3 is a similar view, but with the gate shown in the open position;

Fig. 4 is a front elevation of the gate structure, certain portions being shown in section;

Fig. 5 is a vertical, sectional view of the frame portion of the gate structure, with the drain trough shown in operative relationship with respect thereto;

Fig. 6 is an enlarged detail sectional view, the section being taken on the line 6—6 of Fig. 5; and

Fig. 7 is a fragmentary detail view, enlarged, taken approximately on the line 7—7 of Fig. 2.

It will, of course, be understood that the drawings and description herein contained are illustrative merely, and that various modifications and changes may be made in the structure without departing from the spirit of our invention.

Referring to the drawings, 10 is an ash hopper of any preferred construction. The bottom walls 11 and 12 of the hopper are

preferably inclined, so as to facilitate the discharge of the contents of the hopper when it is desired to empty the same. The wall 12 is provided with a discharge opening 13.

5 A frame 14 is secured to the outer face of the wall 12 of the hopper. The side portions 15 of the frame 14 form a continuation of the sides of the discharge opening, and in like manner the lower portion 16 of the frame 14 forms a continuation of the bottom of the discharge opening.

The top portion 17 of the frame 14 projects to a less extent than the bottom portion 16, and to the extent of its projection forms a 15 continuation of the top of the discharge opening of the hopper.

At the forward end of each of the side portions 15 of the frame 14 there is provided a bearing 18, in which the enlarged central 20 portion 19 of a shaft 20 is journaled. In order to reduce the friction in the bearing, and thereby make the device easier to operate, bearing rollers 21 may be interposed between the enlarged portion 19 of the shaft 25 20 and the outer parts of the bearing structure. Each end of each shaft 20 is squared, whereby the parts secured thereto, as herein-after described, may be securely attached, and the actuation of the same in unison more 30 positively assured.

The gate proper comprises a sector frame 22, which is so formed as to provide an inner 25 pocket in which a refractory lining is mounted. The refractory lining may comprise a plurality of suitably shaped fire brick 23, which are retained in the pocket in any preferred manner.

At one end of the sector frame 22, the wall thereof projects upwardly, as at 27, beyond 40 the surface of the refractory lining 23, said projecting portion 27 being adapted to abut against the top portion 17 of the frame 14 when the gate is in the closed position, and thus limit the same against further movement after the gate is in the proper position 45 to close the opening against discharge of the ashes from the hopper.

At the other end of the sector frame 22, the wall thereof is provided with a projecting 50 lip 28, the outer surface of which constitutes a continuation of the surface of the refractory lining of the gate. The projecting lip 28 serves to direct the drainage water in a manner to be hereinafter more fully set forth.

55 It should here be noted, however, that the outer surface of the lip 28, in the closed position of the gate, comes to a point in proximity to the end of the lower portion 16 of the frame 14, leaving a slight space therebetween 60 through which the drainage may pass. It should also be noted that, when the gate is in the closed position, the lip 28 extends below the plane of the inner surface of the lower portion 16 of the frame 14, for a purpose to 65 be presently explained.

The sector frame 22 of the gate proper is supported by means of side frames 29, the outer portions of which are bolted to the flanges 30 carried by the sector frame 22.

The side frames 29 of the gate structure are 75 clamped to the inner squared end portions of the shafts 20 which are journaled in the side portions of the frame 14, as hereinbefore described.

On the outer squared end portions of the 75 shafts 20 there are mounted counterweights 31. By thus positioning the counterweights on the outside of the side portions of the frame 14, the passageway for the discharge of the ashes will be unobstructed when the gate is in 80 the open position.

The counterweights 31 have bolts 32 mounted therein whereby auxiliary counterweights 33 may be added to secure the proper balance of the gate members.

85 The bolts 32 may also be used for the purpose of securing an operating lever 34 to one of said counterweights. The end of the operating lever may be provided with a depending rod 35, provided with a handle portion 36 for convenient manipulation.

Each of the counterweights may also be provided with a projecting lug portion 37, which is adapted to abut against the side portions 15 of the frame 14, to limit the movement of the gate when the same is brought to 90 the open position.

A drain trough 40 is arranged below the lower front edge of the lower portion 16 of the frame 14, whereby the drainage which passes between said lower edge and the projecting lip portion 28 of the gate member may 95 pass by gravity into the trough.

The trough 40 is supported by means of brackets 41, which are secured to any suitable 100 stationary portion of the structure. It will be noted that the trough is rigidly held in fixed position below the lower portion of the stationary frame 14 of the gate structure. The trough 40 is provided with an outlet nipple 42, to which a pipe 43 may be connected to carry away the drainage.

A plate member 50 is movably mounted below the lower portion 16 of the stationary frame 14 of the gate structure. The preferred means of supporting the plate member 50 comprises an arrangement at each end thereof consisting of a link 51 and a lever 52.

The link 51 is pivotally connected at one end to an upturned end portion 53 of the plate member 50, by means of a bolt 54. The link 51 is pivotally connected at its other end, by means of a bolt 55, to the side portion 15 of the frame 14.

The lever 52 is pivotally mounted on the 110 side portion 15 of the frame 14 by means of a bolt 56. The lower end of the lever 52 is pivotally connected to the upturned portion 53 of the plate member 50 by means of a bolt 57. The other end of the lever 52 carries a 115

bolt 58, which is engaged by the slotted portion 59 of a connecting rod 60. The other end of the connecting rod 60 may likewise be slotted, as at 61, and this slotted portion 61 5 engages a bolt 62 which is carried by the counterweight structure, or any other suitable moving part of the gate structure.

Each of the inner faces of the side portions 15 of the frame 14 is provided with a sector-like projection 70, L-shaped in cross-section, which extends under the end of the sector frame 22 of the gate. The lower end of the projection 70 is curved toward the lower portion 16 of the frame 14, so as to direct any 15 of the drainage which passes down the side portions 15 of the frame 14 into the drain trough 40.

In order to prevent the drainage from running along the under side of the sector portion 22 of the gate, as it would otherwise naturally do, each end of the sector portion 20 22 of the gate is provided with a lip 71, which serves to direct the drainage which passes around the end of the member into the gutter 25 provided by the projection 70.

The operation of the device may now be explained. In the normal closed position of the gate, the parts are in the positions shown in Figs. 1, 2, and 4 of the drawings, the discharge opening of the hopper being closed by the gate proper, whereby the ashes will be permitted to accumulate within the hopper until it is convenient to discharge the same therefrom.

35 It will be noted that when the gate is closed, the plate member 50 will be held in the retracted position entirely under the lower portion 16 of the frame 14, and consequently any drainage resulting from an excess quantity of the water which is used to quench the ashes within the hopper will pass downwardly and be discharged over the lower portion 16 of the frame 14, falling by gravity into the trough 40.

40 Any of the drainage which passes over the upper surface of the gate will in like manner pass through the space between the lip portion 28 of the sector frame of the gate and the lower portion 16 of the frame 14.

45 It may here be noted that the lip 28, projecting below the end of the lower portion 16 of the frame 14, will serve effectively to deflect toward the drain trough any rush of drainage water which may pass downwardly over the inner surface of the lower portion 50 of the frame, and which might otherwise, through its inertia, be spilled beyond the drain trough. It will also be noted that the lip 28 will serve to prevent any of the drainage 55 from passing along the under side of the gate structure, as it might otherwise do.

55 Any of the drainage which passes around the ends of the gate will be caught by the gutter formed by the sector projection 70, 60 and carried thereby until it falls from the

curved inturned portion at the lower end thereof into the drain trough 40.

When it is desired to discharge the ashes from the hopper, the ash car 80, the top of which is shown in Fig. 1 of the drawings, is 70 brought beneath the gate, whereupon the operator pulls down upon the handle rod 35, and thus, through the lever 34 which is connected to the counterweight 31, the shafts 20 are rotated and the gate proper thereby 75 moved to the open position.

During the first part of the movement of the gate, and before the same is brought to a position to permit the ashes to fall from within the hopper, the plate member 50, which is supported by the links 51 and levers 52, will fall by gravity until it extends over the drain trough 40, as shown in dotted lines in Fig. 1, and in full lines in Fig. 3 of the drawings.

85 The movement of the plate member 50, at the beginning of the movement of the gate toward the open position, is permitted by reason of the movement of the bolts 62, which are carried by the counterweight, about the axes 90 of the shafts 20.

After the plate member 50 has reached its final position, and the gate continues its movement to the fully open position, the slotted portions of the connecting rods 60 95 will permit the plate member to stay in its final position, without any further actuation.

It may here be noted that when the plate member 50 extends beyond the lower end of the lower portion 16 of the frame 14, the ashes which are discharged from the hopper will pass over said plate 50 and thereby will be prevented from falling into the drain trough 40.

105 When it is desired to close the gate, the operator pushes upwardly upon the handle rod 35, thereby causing the gate to be returned to its initial position. However, the gate will be returned to such position as to check the further flow of any ashes which 110 may remain in the hopper, before the plate member 50 is retracted to its initial position, this action being permitted by reason of the slots provided in the connecting rods 60.

115 It will be seen that there is thus provided a simple and efficient form of gate structure for ash hoppers and the like, in which the drainage resulting from the excess quenching water will be collected in a stationary drain trough, whence it may be piped away.

120 It will be noted that the drain trough will be effectively protected against the ashes from the hopper falling therein when the same are being discharged from the hopper.

125 It will also be noted that all of the drainage will be effectively guided so as to be properly collected within the drain trough, whether said drainage passes from the bot-

tom of the hopper, over the top surface of the gate, or around the sides thereof.

We claim:

1. The combination, with a hopper having a discharge opening, of a frame surrounding said opening, a movable gate adapted to close the discharge opening, a stationary drain trough arranged below, said frame adapted to receive drainage therefrom, a movable plate member arranged below the lower portion of said frame, and means adapted to actuate said plate member to cause the same to be retracted out of the path of the drainage when the gate is in the closed position and to be extended over the drain trough when the gate is in the open position.
2. The combination, with a hopper having a discharge opening, of a frame surrounding said opening, a movable gate adapted to close the discharge opening, a stationary drain trough arranged below said frame adapted to receive drainage therefrom, a movable plate member arranged below the lower portion of said frame, and means adapted to actuate said plate member to cause the same to be retracted out of the path of the drainage when the gate is in the closed position and to be extended over the drain trough when the gate is in the open position, said means being constructed and arranged whereby the movement of the plate member occurs only during that portion of the movement of the gate when the same is near its closed position.
3. The combination, with a hopper having a discharge opening, of a frame surrounding said opening, a movable gate adapted to close the discharge opening, a stationary drain trough arranged below said frame adapted to receive drainage therefrom, a movable plate member arranged below the lower portion of said frame, and means adapted to actuate said plate member to cause the same to be retracted out of the path of the drainage when the gate is in the closed position and to be extended over the drain trough when the gate is in the open position, said means comprising links pivotally connected to the plate member, levers each having one end pivotally connected to the plate, and rods connecting the other ends of said levers to movable portions of the gate structure.
4. The combination, with a hopper having a discharge opening, of a frame surrounding said opening, an arcuate gate pivotally mounted in said frame and adapted in conjunction therewith to close the discharge opening, a stationary drain trough arranged below said frame adapted to receive drainage therefrom, a movable plate member arranged

adjacent the lower portion of the frame, and means adapted to actuate said plate member to cause the same to be retracted out of the path of the drainage when the gate is in the closed position and to be extended over the drain trough when the gate is in the open position.

5. The combination, with a hopper having a discharge opening, of a frame surrounding said opening, an arcuate gate pivotally mounted in said frame and adapted in conjunction therewith to close the discharge opening, a stationary drain trough arranged below said frame, a movable plate member arranged adjacent the lower portion of the frame, and means adapted to actuate said plate member to cause the same to be retracted when the gate is in the closed position and to be extended over the drain trough when the gate is in the open position, said means being constructed and arranged whereby the movement of the plate member occurs only during that portion of the movement of the gate when the same is near its closed position.

6. The combination, with a hopper having a discharge opening, of a frame surrounding said opening, an arcuate gate pivotally mounted in said frame and adapted in conjunction therewith to close the discharge opening, a stationary drain trough arranged below said frame, a movable plate member arranged adjacent the lower portion of the frame, and means adapted to actuate said plate member to cause the same to be retracted when the gate is in the closed position and to be extended over the drain trough when the gate is in the open position, said means comprising links pivotally connected at their respective ends to the frame and plate member, levers pivoted to the frame each having one end pivotally connected to the plate, and rods connecting the other ends of said levers to movable portions of the gate structure.

7. The combination, with a hopper having a discharge opening, of a frame surrounding said opening, an arcuate gate pivotally mounted in said frame and adapted in conjunction therewith to close the discharge opening, a stationary drain trough arranged below said frame, a movable plate member arranged adjacent the lower portion of the frame, and means adapted to actuate said plate member to cause the same to be retracted when the gate is in the closed position and to be extended over the drain trough when the gate is in the open position, said means comprising links pivotally connected at their respective ends to the frame and the plate member, levers pivoted to the frame each having one end pivotally connected to the plate and rods connecting the other ends of said levers to movable portions of the gate structure, said connecting rods having a slotted connection whereby the movement of the plate member occurs only during that portion of the movement of the gate when the same is near its closed position.

plate member occurs only during that portion of the movement of the gate when the same is near its closed position.

In testimony whereof, we have hereunto
5 signed our names.
